United States Patent Office

Des. 187,304

Patented Feb. 23, 1960

187,304

TRAY FOR MEATS OR SIMILAR ARTICLE

Robert R. Hopper, La Fayette, Calif., and Edmund L. Duskey, Michigan City, Ind., assignors to Kaiser Aluminum & Chemical Corporation, a corporation of Delaware

Application March 25, 1959, Serial No. 55,177

Term of patent 14 years

(Cl. D58—13)

Fig. 1 is a top plan view of a tray for meats or similar article embodying our new design.

Fig. 2 is a side elevational view thereof.

Fig. 3 is a cross-sectional view taken through line 3—3 of Fig. 1.

We claim:

The ornamental design for a tray for meats or similar article, substantially as shown.
